CLAIM

The ornamental design for a load control device, as shown
and described.

DESCRIPTION

This application is also related to U.S. patent application Ser. No. 29/449,242, filed on Mar. 14, 2013 and entitled “Load Control Device,” U.S. patent application Ser. No. 29/449,237, filed on Mar. 14, 2013 and entitled “Load Control Device,” U.S. patent application Ser. No. 29/449,232, filed on Mar. 14, 2013 and entitled “Load Control Device,” U.S. patent application Ser. No. 29/449,257, filed on Mar. 14, 2013 and entitled “Load Control Device,” U.S. patent application Ser. No. 29/449,263, filed on Mar. 14, 2013 and entitled “Load Control Device,” U.S. patent application Ser. No. 29/484,719, filed on Mar. 12, 2014 and entitled “Load Control Device,” and U.S. patent application Ser. No. 29/481,133, filed on Jan. 31, 2014 and entitled “Load Control Device.”

FIG. 1 is a perspective view of an embodiment of a load control device embodying our new design;

FIG. 2 is a front view of the load control device of FIG. 1;
FIG. 3 is a first side view of the load control device of FIG. 1;

FIG. 4 is a second side view of the load control device of FIG. 1;

FIG. 5 is a top view of the load control device of FIG. 1; and,
FIG. 6 is a bottom view of the load control device of FIG. 1.

The broken lines shown herein are included for the purpose
of illustrating an environment of the article and form no part
of the claimed design. Additionally, the rear view forms no
part of the claimed design.
